UNITED STATES PATENT OFFICE.

OLAF JOEL WESTMAN, OF LINCOLN, NEBRASKA.

SHORING.

1,330,290.

Specification of Letters Patent. Patented Feb. 10, 1920.

Application filed January 16, 1918. Serial No. 212,013.

To all whom it may concern:

Be it known that I, OLAF JOEL WESTMAN, citizen of the United States, residing at Lincoln, in the county of Lancaster and State 5 of Nebraska, have invented a certain new and useful Improvement in Shoring, of which the following is a full, clear, concise, and exact description.

This invention relates to improvements in 10 adjustable and portable trestles and more particularly to a combination trestle and scaffold support adapted primarily for use as shoring in the construction of concrete floors and ceilings.

15 It is well known that in the construction of concrete floors and ceilings it is necessary to provide some means for temporarily supporting the molds during the pouring and setting of the concrete. Heretofore, it has 20 been common practice to provide T-shaped supports at various intervals beneath the molds for this purpose. These supports were rigidly constructed of heavy lumber, but owing to the fact that distances between 25 floors and ceilings vary in different buildings, the supports were not of universal application and oftentimes had to be either shortened or replaced by new ones of different dimensions when different floor spacings 30 were encountered, either in the same building or in the erection of others. This resulted in the loss of much valuable lumber and also necessitated the expenditure of time and money in the construction of new supports. 35 Furthermore, these posts or supports were removed, after the floor or ceiling had been completed, by hammering, which caused much jarring to the building and particularly to the floors between which the supports were erected.

40 One object of the present invention, therefore, is to provide a device, of the character described, which will effectively overcome these various disadvantages and one which 45 will be of universal application, simple in construction and operation and economical to manufacture.

Another object is the provision of means whereby the trestles or supports may be 50 readily and quickly removed after the floors or ceilings have set, without hammering them or in any other manner causing the said floors or ceilings to be jarred or otherwise subjected to strain and possible injury.

55 Other objects and advantages will be apparent from the following description taken

in connection with the accompanying drawings wherein the preferred embodiment of the invention is illustrated.

Figure 1 is a front elevation of the trestle 60 illustrating the same in operative position.

Fig. 2 is a side elevation, and

Fig. 3 is a section taken on line 3—3.

Referring more in detail to the drawings, the device is shown as comprising a rectangular frame 10 preferably constructed of vertical members 11 and horizontal members 12, said frame being reinforced by a plurality of braces 13. Adjustably secured by means of clamps 14 to the vertical members 11 of the frame 10 are uprights 15. The clamps 14 comprise substantially U-shaped brackets 16 which embrace the adjustable uprights 15, one end of each of said U-shaped brackets 16 being secured by means 70 of a bolt 17 to one face of the vertical members 11 of the frame 10. On the opposite face of the frame, short straight pieces 18, which form a part of the clamps 14, are secured by means of the same bolts (17) which hold the 75 U-shaped brackets 16 to the members 11, said short pieces 18 extending beyond the sides of the frame 10, substantially as shown, and providing means for the reception of the ends of the bolts 19 which are carried by the 80 corresponding ends of the U-shaped brackets 16 and which serve as means whereby said brackets may be firmly clamped about the uprights 15 to hold them in their adjusted 85 positions.

90 From this it will be noted that by merely loosening the bolts 19 of the clamps 14 that the adjustable uprights 15 may be moved up or down relatively to the frame 10 so as to provide for various floor spacings. In 95 this manner, the trestle may be adjusted to various heights and, therefore, is of universal application for purposes of floor and ceiling shoring. On the other hand, if it is desired to remove the adjustable uprights 15 100 from the frame 10, this may be accomplished by merely removing the bolts 17. In this manner, the adjustable uprights 15 are released from the frame 10, substantially as shown in dotted line in Fig. 2, thus permitting 105 said frame 10 to be used independently of the other parts of the trestle, if desired, in the capacity of a support for scaffolding of various types.

110 The joists and girders of a floor or ceiling in the process of construction are designated as 21. A plurality of supporting up-

rights are illustrated at 20, said uprights being mounted on the upper edge of the frame 10 preferably directly over the upright members 11 thereof and being of sufficient length 5 to support the floor or ceiling by engagement with the girders thereof, substantially as shown. The supporting uprights 20 together with the frame 10, it will be noted, support the entire weight of the mold during the pouring and setting of the concrete. 10 The adjustable uprights 15 which extend upwardly from the frame 10 are used merely to gage the distance between the floors and to reinforce said supporting uprights 20. 15 It will be noted from the drawings that the uprights 15 support none of the floor weight, but merely extend upwardly far enough to overlie opposite sides of a plurality of the girders and to embrace the same whereby 20 the trestle, when positioned, is held against accidental transverse displacement. These adjustable uprights 15 also provide means whereby the supporting uprights 20 may be held in place after they have once been positioned. 25 The means for so holding these uprights 20 in place is shown in the drawings in the form of members 22 temporarily secured to the beams 20 and 15 by means of nails, screws or any other suitable fastening means. It is, of course, obvious that other means of retaining the supporting beams 20 in position may be provided, if desired.

After the concrete of the floor or ceiling, which is being constructed, has been poured and has set, the trestle is removed by merely removing the temporary retaining means 22 and springing the supporting uprights 20 out of position. The adjustable uprights 15 may then be quickly lowered by merely loosening the bolts 19 of the clamps 14, thus permitting said uprights to slide to their lowermost positions. However, if desired, as above set out, the adjustable uprights 15 together with the clamps 14 may be removed 45 altogether from the frame 10 by removing the bolts 17.

It will be noted that the device herein described is not limited to shoring purposes, but may also be used in the erection of scaffolding where adjustable supports are desired. If scaffolding of the ordinary type, wherein the supports are rigid and non-adjustable is desired, however, the frame 10, after the trestle has been disassembled, may 55 be used for this purpose, as above pointed out. As short pieces of lumber, such as the uprights 20 which are used in the present device for supporting the weight of the floor or ceilings being constructed, are always 60 available during the construction of a building, it is obvious that the necessity of cutting long posts or supports, such as was common in the method of shoring heretofore practised, is obviated. It will also be noted 65 that it is not necessary in the use of the

trestles herein described to hammer the same out of position after the floor has hardened, the device being removed as above described by merely springing the supporting uprights 20 out from under the girders. 70

It is not desired to limit the invention illustrated and described herein except where limitations appear in the appended claims.

Having thus described my invention, what 75 I claim as new and desire to secure by Letters Patent of the United States is:—

1. A trestle of the type described, comprising a frame, upright members slidably mounted thereon and a plurality of supporting uprights mounted on the top edge of said frame and temporarily secured to said 80 slidable uprights and adapted to support the weight of a floor during construction.

2. A device for shoring floors and ceilings during construction, comprising a frame, uprights carried by said frame, means whereby said uprights may be moved relative to said frame into contact with the sides of a plurality of the girders of said 90 floor or ceiling, a plurality of supporting members mounted intermediate said girders and said frame and supported by the latter, and means for temporarily securing said supporting members to said uprights. 95

3. In a temporary building construction, the combination with a floor, of means for supporting the same comprising members arranged end to end in line with the compression thrust caused by the weight being 100 supported, and means secured to said members temporarily to hold them in line, as a toggle, during construction, but permitting said toggle to break when removed therefrom thereby shortening the effective length 105 of the composite supporting means and permitting ready removal of the members comprising the same.

4. In a temporary building construction, the combination with a floor, of means for 110 supporting the same comprising members arranged end to end in line with the compression thrust caused by the weight being supported, and means adjustably secured to one of said members and temporarily secured to the other of said members to hold said members in line as a toggle during construction, but permitting said toggle to break when removed therefrom. 115

5. In a temporary building construction, 120 the combination with a concrete form, of means for supporting the same comprising two vertical compression members arranged end to end, the lower one of said compression members being a permanent portable 125 structure of fixed height and the other of said compression members being temporary and cut to length to meet requirements, an auxiliary member adjustably clamped to said permanent member, detachably secured 130

to said temporary member and of a length sufficient to securely hold said two members in line as a toggle despite variations in the length of different temporary members, the 5 detachment of said auxiliary member permitting said toggle joint to break, to permit the removal of said members.

6. In a temporary building construction, the combination with a concrete form, of 10 means for supporting the same comprising two vertical compression members arranged end to end, the lower one of said compression members being a permanent portable structure of fixed height and the other of 15 said compression members being temporary and cut to length to meet requirements, an auxiliary member longer than the maximum length of any one temporary member, whereby it may be detachably secured to a temporary member and extend above and below the same, being temporarily engaged at its upper end by said concrete form and being adjustably secured at its lower end to said permanent member, whereby it may 20 extend a uniform amount above said temporary member and may hold said temporary and said permanent members in alignment.

7. In a temporary building construction, 30 the combination with a horizontal concrete form of a plurality of supporting units therefor, each comprising two vertical compression members arranged end to end, the lower one of said compression members being a permanent portable structure of fixed height and the other of said compression members being temporary and cut to length to meet requirements, an auxiliary member adjustably secured near its lower end to said 35 permanent member and extending upwardly along said temporary member and above the latter, being temporarily secured to said temporary member, and means temporarily bracing said units in spaced relation.

40 45 8. In a temporary building construction, the combination with a pair of compression

members arranged vertically in end alignment and adapted to support the required weight, of a thin auxiliary member secured thereto, said compression members being 50 held against movement as a toggle by said auxiliary member and the latter being arranged in the plane in which said members move when said auxiliary member is withdrawn.

55 9. In a temporary building construction, the combination with a plurality of rectangular frames of fixed height, of a plurality of temporary upright members for each frame, the length of which is variable, 60 said upright members being supported on said frames in vertical alignment therewith, said frames having narrow bases whereby the weight being supported tends to move said members and frames out of alignment, 65 and thin auxiliary members arranged in the plane of such movement and secured to said members and said frames to resist such movement until the completion of the construction.

70 10. In a temporary building construction, a plurality of frames of fixed height, a plurality of upright members for each frame, a horizontal structure supported by said upright members, the latter resting on said 75 frame in the same plane therewith, an auxiliary vertically movable member extending along both said frame and an upright member thereon, a clamp carried by said frame and embracing said auxiliary member to 80 permit vertical adjustment of the latter, the upper end of said auxiliary member being engaged by said horizontal structure, and means for temporarily connecting and securing a plurality of said upright members. 85

In witness whereof I hereunto subscribe my name this 7th day of January, A. D., 1918.

OLAF JOEL WESTMAN.
